BOW NECKTIE

William Donald Blackwell, Coconut Grove, Fla., assignor to Bronzini, Ltd., New York, N. Y., a corporation of New York

Application January 13, 1951, Serial No. 13,799

Term of patent 14 years

(Cl. D3—16)

To all whom it may concern:

Be it known that I, William Donald Blackwell, a citizen of the United States, residing at Coconut Grove, Florida, have invented a new, original, and ornamental Design for a Bow Necktie, of which the following is a specification, reference being had to the accompanying drawing, forming a part thereof, in which

Fig. 1 is a top plan view of the untied bow necktie, illustrating the position of the figures of various size comprising the pattern in such a manner that the smallest figures of the pattern appear on the portions used to form the knot of the tie while the larger figures of the pattern appear on the portions used to form the wings of the tie.

Fig. 2 is a front view of the bow necktie shown in Fig. 1 as it appears in tied position, illustrating the position of the figures of various sizes in such a manner that the smallest figures of the pattern appear on the knot portion presenting a replica in miniature of the pattern of the larger figures appearing on the wing portions.

I claim:

The ornamental design for a bow necktie, as shown and described.

WILLIAM DONALD BLACKWELL.
